UNITED STATES PATENT OFFICE.

FELIX O'DONNELL, OF PAWTUCKET, RHODE ISLAND, ASSIGNOR OF ONE-HALF TO SUSAN A. BROWN, OF PAWTUCKET, RHODE ISLAND.

SHUTTLE-POSITIONING DEVICE FOR LOOMS.

No. 827,937.

Specification of Letters Patent.

Patented Aug. 7, 1906.

Application filed April 20, 1905. Serial No. 256,601.

To all whom it may concern:

Be it known that I, FELIX O'DONNELL, a citizen of the United States, residing at the city of Pawtucket, in the county of Providence and State of Rhode Island, have invented certain new and useful Improvements in Shuttle-Positioning Devices for Looms, of which the following is a specification, reference being had therein to the accompanying drawings.

This invention relates to a shuttle-positioning device, and has for its object to produce a device that will engage and force the shuttle completely into the shuttle-box when a small amount of it projects therefrom and place said shuttle exactly in the required position in the box.

A further object of the invention is that if for any reason the shuttle only partly enters the box and is not in far enough to be acted upon and moved farther by a positioning-arm then the shuttle as it is being brought forward on the lay will engage said arm and force it backward and through suitable mechanism throw off the operating-lever and stop the loom.

It is found in practice that when the shuttle is thrown across the lay it is not always sent with a uniform velocity for various reasons—sometimes it does not entirely enter the box and sometimes it enters with considerable force and rebounds therefrom. In the operation of weft-replenishing mechanism on the looms it is of vital importance to the successful operation of the same that the shuttle should be in a position exactly beneath the bobbin-holder when the mechanism operates to strike a bobbin down into the same. Also in the operation of the ordinary loom it is found that the loom operates to much better advantage if the shuttle is well back in the box with one end resting against the picker-stick. I have therefore devised this simple means of exactly positioning the shuttle in the box or, on failing to do so, to automatically stop the loom, so that the shuttle may be replaced by hand, thereby effectually preventing the weaving of bad places in the cloth.

The invention is fully set forth in this specification and more particularly pointed out in the appended claims.

In the accompanying drawings, Figure 1 is a perspective view showing a portion of the

lay, the breast-beam of a loom, and the shuttle in the shuttle-box, also showing the positioning-arm and the mechanism operated thereby to stop the loom when it brings up positively against the side of the shuttle. Fig. 2 is a plan view showing a portion of the breast-beam, the lay, and the shuttle, also the positioning-arm in position to act on said shuttle and drive it to its proper place in the box. Fig. 3 is a sectional elevation on line 3-3 of Fig. 2. Fig. 4 is an enlarged detail view, partly in section, showing the latch-bolt and its connection to the rocker-shaft.

Referring to the drawings, at 1 is the usual loom breast-beam, broken away at one end to better show the mechanism beyond. At 2 is the usual loom-operating lever, that extends up through said beam and works in the slot 3. A portion of the lay is shown at 4, and a portion of the shuttle 5 is shown in the shuttle-box 6, with its ends 7 projecting slightly out of the same.

At 8 is the positioning-arm, which is set at right angles to the breast-beam and is hung to be moved endwise in bearings 9 and 10, supported from said beam. The stiff coil-spring 11 is wound around one end of this arm, one end of said spring being in contact with the bearing 10 and the opposite end pressing against the shoulder 12 on said arm, normally holding the same in its outward position against the stop-pin 13. On the contact end of this arm is the shoe 14, that is faced with leather or other suitable material 15. This shoe is designed to engage the tapering end of the shuttle, (if said end should project beyond the box as said shuttle is being brought forward by the lay,) and by such engagement force the shuttle inward to its required position. On the under side of the arm 8 is the recessed portion 16, which is provided with a notch 17. Connected to the rocker-shaft 18 is the guide-collar 19, in which collar the latch-bolt 20 works and is normally held in its outward position against the said arm 8 by the tension of the coil-spring 21.

At 22 is one of the bearings that supports the rocker-shaft beneath the breast-beam, and at 23 is the knock-off finger mounted on said shaft. This finger has one end extending upward to engage the arm 24, through which arm the operating-lever 2 is thrown off.

The operation of the device may be further described as follows: When the shuttle is

- thrown across the loom, it is supposed to enter the shuttle-box, where its velocity is checked by various means and to stop in a given position with its end resting against the picker-stick; but it is found in practice that the shuttle does not always do this. Sometimes it enters the box too fast and rebounds therefrom, leaving the end projecting slightly, and sometimes it does not quite enter the box, in both of which cases it should be carried forward to the required position. The positioning of the shuttle is especially necessary on a loom equipped with weft-replenishing mechanism in which a bobbin is held in a given position to be struck down into the shuttle. It is obvious that by the use of this mechanism the shuttle must be in a position directly beneath the bobbin in order to receive said bobbin from its holder.
- In order to be sure that the shuttle is carried to its proper place each time on the replenishing end of the loom, I have located the positioning-arm 8 on the breast-beam and placed behind it a spring of sufficient strength to yield only when said arm strikes squarely against the side of the shuttle. This arm is arranged to engage the beveled end of the shuttle (if the same is projecting from the shuttle-box) as said shuttle is being brought forward on the lay and by such engagement move said shuttle inward to its required position in the box to a point directly beneath the bobbin to be delivered therein. Should the shuttle be extending out of the box too far when brought forward on the lay, so that the arm could not engage its beveled end, then the side of said shuttle would strike against the arm and force it backward against the tension of its spring 11, causing the notch 17 to engage the latch-bolt 20, turn the same back, rotate the rocker-shaft, and by the movement of the finger 23 fixed thereon the operating-lever is released and the loom stopped.
- The device is extremely simple in construction and effective in its operation and may be readily attached to any loom.
- Having thus described my invention, what I claim as new, and desire to secure by Letters Patent, is—
1. A device of the character described comprising an arm or member for engaging the shuttle as the latter is moved forward with the lay of the loom, and means carried by said arm for yieldingly holding the same in a normally outward position.
  2. A device of the character described comprising an arm or member provided at one end with a shoe for engaging the shuttle as the latter is moved forward with the lay of the loom, and means carried by said arm for yieldingly holding said shoe in a normally outward position.
  3. A device of the character described comprising an arm or member for engaging the shuttle as the latter is moved forward with the lay of the loom, and a spring carried by said arm for yieldingly holding the same in a normally outward position.
  4. A device of the character described comprising a shuttle-engaging arm mounted in bearings, and means carried by said arm for yieldingly holding the same in a normally outward position.
  5. The combination with a longitudinally-reciprocable arm or member arranged to intercept a projecting portion of a shuttle as the latter is carried forward by the lay of the loom, and means carried by said arm for holding the same in a normally outward position, of means for stopping the loom when said arm or member yields to the movement of said shuttle.
  6. The combination with the breast-beam of a loom of an arm or member for engaging a projecting portion of a shuttle as the latter is moved forward by the lay of the loom, a spring for holding said arm or member normally forward, a shaft mounted adjacent said breast-beam and provided with a member normally in engagement with said first-mentioned arm or member, whereby said shaft will rock when said arm or member moves against the action of its spring, and means controlled by said shaft for stopping the loom.

In testimony whereof I affix my signature in presence of two witnesses.

FELIX O'DONNELL.
